(57) **CLAIM**

The ornamental design for a table, as shown and described.

DESCRIPTION

FIG. 1 is a perspective view of a table showing my new design;

FIG. 2 is a front elevational view thereof; and,

FIG. 3 is a top view thereof.

The views of the table not shown form no part of the claimed design. The broken lines depicting legs, hardware and surface ornamentation represent environmental elements only and form no part of the claimed design.

1 Claim, 3 Drawing Sheets

FIG. 1

FIG. 2

FIG. 3
